PROCESS FOR PARTIAL OXIDATION OF GASEOUS HYDROCARBONS

Filed March 21, 1928

Inventor

WARREN K. LEWIS

By his Attorney John straw

UNITED STATES PATENT OFFICE

WARREN K. LEWIS, OF NEWTON, MASSACHUSETTS, ASSIGNOR TO STANDARD OIL DEVELOPMENT COMPANY, A CORPORATION OF DELAWARE

PROCESS FOR PARTIAL OXIDATION OF GASEOUS HYDROCARBONS

Application filed March 21, 1928. Serial No. 263,409.

The present invention relates to the art of treating hydrocarbon materials to form valuable liquid products and more specifically to an improved process for oxidation of hydrocarbons with air to form alcohols, aldehydes, acids and other oxygen-containing products. My process will be fully understood from the following description and the drawing which illustrates one form of apparatus suitable for the process.

The drawing is a semi-diagrammatic view in elevation of an apparatus constructed according to my invention and indicates the flow of material through the apparatus. 15 In a previous application, Serial No. 190,728 filed May 12, 1927 by W. K. Lewis and P. K. Frolich and in a second application Serial No. 226,076, filed October 14, 1927 by P. K. Frolich, an oxidation process for obtaining normally liquid oxidation products such as alcohols, aldehydes, acids and other oxygen-containing compounds was disclosed. The use of air for oxidation of hydrocarbons is economically advantageous because of its 20 availability and it is also highly advantageous to recirculate unoxidized hydrocarbon through a zone of oxidation if one is to obtain large yields. The present invention comprises an improved method for oxidizing 25 hydrocarbon by means of air and separating the unoxidized hydrocarbon from residual products whereby the hydrocarbon may be economically recirculated.

Referring to the drawing, the reference 30 character 1 designates a high pressure source of hydrocarbons which may be natural or artificial hydrocarbon gas, a single pure compound, or a hydrocarbon-containing mixture. This raw material, which will hereafter be 35 termed hydrocarbon, is fed by a pipe 2 to a manifold 3 and then to a plurality of coils *a*, *b*, *c*, and *d*, which are carefully distributed throughout the interior of the reactor 4 and in which the hydrocarbon is preheated. The 40 reactor may be of any suitable design but is preferably a heavy steel shell adapted to withstand pressures in excess of 3,000 lbs. per square inch and a temperature of 600° C. or higher. The reactor is suitably lagged and 45 may be fitted with other heat exchanging coils

in addition to *a*, *b*, *c*, and *d*, for circulation of another cooling medium but which have not been shown on the drawing for the sake of simplicity. The body of the reactor may be otherwise empty or it may be partially filled with catalytic material, the nature of which was disclosed in application Serial No. 190,728. The hydrocarbon feed may be distributed throughout the coils *a*, *b*, *c*, and *d*, so as to absorb the heat evolved by oxidation and to maintain all parts of the reactor at approximately the same temperature, which is predetermined and called the reactor temperature. Part of the hydrocarbon is passed by line E through a heat exchanger F and is preheated by hot products from the reactor 4.

The preheated hydrocarbon is passed to a manifold 5 and is thence conducted to a coil 6, wherein the hydrocarbon is heated to a temperature somewhat below that of the reactor and is then discharged into a mixing pipe 7. A by-pass line 6a is provided so that all or part of the hydrocarbon may be shunted around the coil 6 after the reactor has reached its proper temperature. Air is compressed by a suitable compressor 8 and is also discharged into mixing pipe 7, wherein it is thoroughly mixed with the hydrocarbon. The mixture is then discharged into the reactor 4 and the heat of reaction immediately raises the temperature to the predetermined degree. If desired, part of the air may flow through pipe 9 and a plurality of branch pipes *a'*, *b'*, and *c'* in regulated quantities.

The mixture from the reactor is discharged into exchanger F, then into a cooler 10 and through a valve 11 into the middle of a rectifying tower 12 which is fitted with cooling coil 13 and heating coil 14 in its upper 90 and lower portions respectively. The liquid flowing from the base of tower 12 consists of the normally liquid oxygen-containing products and hydrocarbons, such as propane and heavier hydrocarbons, although ethane 95 may be included, if desired. This mixture flows through line 15 and the reduction valve 16 into a second tower 17 which is fitted with cooling and heating coil 18 and 19 as will be understood. The major quantity of the 100

normally liquid oxygen-containing products is obtained as liquid from the base of tower 17 and is conducted to storage (not shown) through line 20 and cooler 21.

Vapor from the top of tower 17 is conducted to a condenser 23 by line 22 and is condensed therein to a liquid preferably under pressure. The liquid which may contain small quantities of oxygen-containing products may then be conducted by line 24 to scrubbing system comprising a tower 25. Hydrocarbon is admitted at the base of tower 25 by a spray pipe 26 and a solvent, immiscible therewith and having a greater density than the hydrocarbon is admitted at the top through spray 27. In making its way to the bottom the solvent extracts the oxygen-containing products and flows through pipe 28 to tank 29. Solvent may be recirculated through line 31 by pump 30 and fresh or stripped solvent is admitted by line 32. The rich solvent may be drawn from tank 29 through a line 33 to stripping stills (not shown) for recovery of the oxidation products, as will be readily understood. Hydrocarbon flows from tower 25 by line 34 and is pumped by pump 35 to the source 1 for recirculation.

Fixed gas which is discharged from the top of tower 12 by line 36, comprises methane, ethane, nitrogen and carbon dioxide and is conducted to a scrubbing tower 37. An alkaline solution such as aqueous caustic soda is admitted by spray pipe 38 and in running down through the tower absorbs the carbon dioxide. The solution may be recirculated by lines 39 and 42 and pump 41. Spent soda may be withdrawn from the tank 40 by line 44 and fresh soda admitted to the system by 43.

The gas now free of carbon dioxide flows by line 45 to a heat recuperator system indicated generally at 46 in which the mixture is partially liquefied. The recuperator system may be in any advantageous form adapted for the efficient cooling of incoming materials by the cold effluent fluids, and is preferably arranged to take advantage of counter-flow principles. Precooled and partially liquefied mixture of nitrogen and hydrocarbon flows from recuperator 46 then flows by line 47 to a coil 48 which is submerged in the liquid, in a still 49. The still is fitted by a tower 50 into which the partially liquefied mixture is discharged by line 51 fitted with an expansion valve R. The mixture is rectified in tower 50 and the vapor fraction, comprising substantially nitrogen, escapes by vapor line 52 to recuperator system 46 and thence by line 53 to be discarded by line 54. A part of this nitrogen is recompressed by compressor 55 and after cooling in a cooler 56 is conducted to the recuperator 46 by line 57. The gas is partially liquefied in 46 and passes by line 58 to coil 59 which is submerged

in the liquid in still 49. From coil 59 the liquid is conveyed to the top of tower 50 by line 60 where it serves as reflux in effecting rectification after expansion through valve R'. Hydrocarbon, substantially free of nitrogen, comprising methane, ethane and propane, is withdrawn from still 49 by line 61 and after passing through recuperator 46, it is returned by line 62 to booster 63 and by line 64 to the source of hydrocarbon for recirculation through the system.

In the previous applications above mentioned, the conditions for oxidations have been fully disclosed and it is sufficient to say that the reactor 4 is maintained at temperatures between 350 and 600° C. and under pressure preferably between 1500 and 3500 lbs. per square inch. The mixture of hydrocarbon and air is passed at a high rate of flow preferably over a catalyst, for example, metallic nickel, in the reactor and the mixture is discharged into tower 12 for separation into liquid and gas. Pressure prevailing in 12 shall be below critical pressure of the liquid mixture boiling in base and preferably below 500 lbs. per square inch. Temperature at top of tower 12 is such that butane will be condensed and may be such that propane is refluxed as will be understood. In this manner substantially all of the hydrocarbons heavier than propane may be obtained as a liquid from the base of tower 12 and propane may be included in the liquid, if desired, or in the vapor or in both liquid and vapor. I contemplate operation in either of these manners, but prefer to include propane in the gas from tower 12 since otherwise low temperature is necessary at coil 13 and must be produced by refrigeration, as is apparent.

Pressure may be reduced at valve 16 and preferably only sufficient pressure is held on tower 17 to insure that the hydrocarbon will be condensed by the cooling medium in cooler 23, such pressure may be between atmospheric and 100 lbs. per square inch and will vary according to the composition of the hydrocarbon feed as will be understood.

The solvent used in scrubber 25 is preferably an oxygenated solvent or one containing an hydroxyl group, such as water, methyl alcohol, ethyl alcohol, glycerine or ethylene glycol, or mixtures of such solvents with each other or with other substances.

The liquefaction system illustrated is similar to that known as the Linde system although other methods of liquefaction may be used as will be understood. Pressure in tower 50 is preferably above atmospheric and temperature is below the critical temperature of methane so that methane may be obtained substantially free from nitrogen, which passes from the tower by line 52 as indicated above. Operation of the liquefaction system is well known and further details need not be given.

I prefer to operate my system so that substantially no methane will be introduced into tower 17 and so that hydrocarbons heavier than propane will not go to the liquefaction system. If propane be present in a mixture with methane, ethane and higher hydrocarbons, the propane is treated preferably with methane and ethane in the liquefaction system or it may be included with the higher hydrocarbons in the subsequent distillation for separation of the oxygen-containing products. My process is well adapted for use with a starting material, such as natural or artificial hydrocarbon gas and if the quantity of hydrocarbon lower than ethane is small, they need not be recirculated and tower 17 and 25 may be omitted.

My process is not to be limited by any theory of the mechanism of the oxidation or by any specific example given merely by way of illustration but only by the attached claims in which I wish to claim all novelty inherent in the invention.

I claim:

1. A process for the treatment of normally gaseous hydrocarbon mixtures to form normally liquid oxygen-containing products, comprising the steps of passing gaseous hydrocarbons and air under high pressure and elevated temperature into a zone of partial oxidation, passing the resulting products from said zone of partial oxidation and reducing the temperature whereby liquid and vapor phases are produced, reducing the pressure and rectifying the mixture to yield a gas containing nitrogen of the air and hydrocarbons including methane and propane, and a liquid comprising normally liquid oxygenated products, cooling said gas under pressure to a temperature sufficiently low to liquefy the greater part of the methane, rectifying the liquefied gas to produce nitrogen gas substantially free from hydrocarbon gas and liquid, returning the hydrocarbon to the process and separately withdrawing nitrogen.

2. In a process according to claim 1, the steps of partially liquefying the vapor comprising gaseous hydrocarbon and nitrogen by expansion, separating vapor from liquid so produced, recompressing residual vapor and re-expanding it for additional liquefaction.

3. Process according to claim 1 in which the vapor comprising gaseous hydrocarbon and nitrogen is scrubbed free of carbon dioxide prior to partial liquefaction.

WARREN K. LEWIS.
